UNITED STATES PATENT OFFICE

106,925

DESIGN FOR A LAMP CLOSURE

Howard C. Mead, Anderson, Ind., assignor to General Motors Corporation, Detroit, Mich.,
a corporation of Delaware

Application April 26, 1935, Serial No. 56,592

Term of patent 7 years

To all whom it may concern:

Be it known that I, Howard C. Mead, a citizen of the United States and a resident of Anderson, county of Madison, State of Indiana, have invented a new, original, and ornamental Design for a Lamp Closure, of which the following is a specification, reference being made to the accompanying drawing, forming a part thereof.

In the drawing:

I claim:

The ornamental design for a lamp closure, as shown.

HOWARD C. MEAD.
